MAP-DISPLAYING EASEL AND CONTAINER SUPPORT

Albert O. Miller, Jr., San Gabriel, Calif.

Application May 26, 1947, Serial No. 750,619

3 Claims. (Cl. 248—197)

1

This invention relates to a collapsible easel adapted to adjustably display a map or similar device and provide in association therewith a folding shelf adapted to support a sorting case or other rack or container.

This invention has particular utility for Postal Service employees who, in order to meet the requirements for advancement in the service, are required to spend much time in familiarizing themselves with the names and locations of large numbers of post offices, as well as the various rail, bus, and air routes leading thereto, within the respective districts within which they already are operating or the districts to which they are endeavoring to be advanced. The type of study required necessitates the use of a map of the district under consideration and a sorting case containing a large number of pigeonholes, each of which is identified with one or more of the transportation routes leading to the various post offices located in the area shown on the map. The usual equipment also includes a large number of cards, each bearing the name of one of those post offices, and the method of study entails picking the cards up one at a time, reading the name of the post office indicated thereon, and placing the card in the pigeonhole which is identified with the name of the transportation medium best suited for carrying the mail to the named post office under the circumstance and from the starting point assumed as the basis of study.

The standard sorting case is foldable and hence readily portable, as is also the map, so that the employees are accustomed to carrying them with them and, whenever time which otherwise might be wasted becomes available, an ambitious employee can set them up and proceed with his studying. Heretofore, however, it has been necessary to support both the map and the sorting case in any make-shift manner made possible at the time when and place where such impromptu studying is being done, such as by placing the opened case in the seat of a chair leaning against the chair's back, and hanging the map over the back of the same or another chair. Such an arrangement, as is readily understandable, is not conducive to the best results since it fails to locate the apparatus at the height most comfortable to the student, nor the map in the best position with relation to the sorting case in order to permit the student's rapid and facile observation of both. The present invention, therefore, seeks to provide a collapsible easel capable of supporting the type of sorting case and map referred to in the most readily accessible position for both, so as to

2

afford the greatest comfort and convenience for the student, and a minimum of distraction from his concentration upon his studies.

A further object of my present invention is to provide an easel of the general type indicated which may be set up and knocked down quickly and efficiently and readily carried about in a small space.

Accordingly, it is an object of the invention to provide an article of the character described having an outwardly projecting supporting shelf, simultaneously and cooperatively collapsible with said easel and having an upper, notched rib on said shelf adapted to receive in said notches the 15 easel legs upon folding.

Still another purpose is the provision of such an easel having a longitudinally adjustable, map-elevating holder operatively associated therewith.

Other objects and advantages of the invention will be apparent from the following description and claims, the novelty consisting in the features of construction, combination of parts, the unique relations of the members and the relative proportioning, disposition, and operation thereof, all as 20 more completely outlined herein and particularly pointed out in the appended claims.

In the drawings, which form part of the present specification:

Figure 1 is a perspective view of my map-supporting easel, showing the sorting case mounted thereon ready for use.

Figure 2 is a perspective view of the same as seen from the rear with the sorting case removed.

Figure 3 is a front perspective view of the easel 25 alone, shown in collapsed position.

Figure 4 is a rear perspective view of the folded easel of Figure 3.

Figure 5 is a perspective view of the joint connecting the crossbar and slideable rod.

As illustrated, my easel 10 is constructed of 30 three upright supporting legs 12, 14, and 16 pivotally joined together by a horizontally disposed pin 18 inserted through their adjacent upper extremities. The outer legs 12 and 16 have their top, inner engaging faces tapered or sloped with respect to their sides so as to smoothly rotate about the pivot pin 18 against the opposite abutting sides of the middle leg 14 disposed therebetween.

A generally rectangular shelf 20 is hingedly attached to the front edges 21 of both side legs 12 and 16 so as to be movable between an outwardly projecting horizontal position (Figures 1 and 2) and an upwardly folded position (Figures 3 and 4) wherein its upper face 22 is disposed adjacent

the front edges 21 of the legs. Each outer leg 12 and 16 has attached to its inner side a reinforcing block 26 of equal width and having wedge-shaped ends 28 and 30, the reinforcement being mounted along the shelf attachment line so as to provide a wider mounting surface for the shelf hinge 32 along each leg.

The shelf 20 is provided with a lower, transverse, rearwardly projecting supporting arm 34, the free rear end of which is connected to the center leg 14 by a composite link 40 composed of a pair of flat slats or arms 42 and 44 disposed on opposite sides of and pivotally connected to the arm 34 at their one end and in similar engagement with opposite sides of the center leg 14 at their other end, being held together at their ends by transverse pivot pins, 46 and 48 respectively. By this construction, it will be seen that upon opening the easel from the folded position of Figures 3 and 4, the shelf 20 swings down while the center leg simultaneously moves back to assume the position of Figures 1 and 2 wherein the link 40, arm 34, and shelf 20 are all horizontally aligned.

A wire catch 50 is so mounted on the center leg 14 that when desired it may be swung out to engage the lower face of the upswung shelf and thus retain the same against the edges of the three legs when all are disposed in a common plane. On the upper face 22 of the shelf there is located a longitudinal, discontinuous rib 52 spaced somewhat forward of the rear edge of the shelf and provided with a series of transverse recesses 54 (three in number) within which the easel legs are disposed to seat when the easel is folded. In other words, the upswung shelf completely abuts against the legs 12, 14, and 16 along its entire width, the slots 54 in the rib being shaped to more or less snugly embrace the thickness of the center leg 14, or in the case of the outer legs 12 and 16, to embrace the thickness of the leg plus that of the reinforcing block 26 at its wedged end. Such arrangement results in a very strong and firm easel assembly in either collapsed or open position, which can be easily carried about when thus compactly collapsed, without fear of its accidentally opening up.

Along the rear edge of the center leg 14 there is disposed an elongated, generally rectangular rod 56 movably retained thereagainst by a series of U-shaped staples or brackets 58, 60, and 62, the rod being longitudinally slidably beneath said embracing brackets so that it may be extended beyond the top of its supporting leg 14. A crossbar 64 can be removably attached at its center to the upper end of the slidable rod 56, any suitable means of attachment being satisfactory provided the crossbar 64 is retained substantially horizontal so as to support the map 66, the upper edge 67 of which is laid over the crossbar 64 so as to hang down a short distance in back thereof. The means for removably attaching the crossbar 64 to the upper end of the slidable rod 56, which have been chosen for illustration comprises a short tongue 68 rigid with and projecting upwardly beyond the upper end of the slidable rod 56, and a substantially complementary socket 70 which is conveniently formed at the midportion of the crossbar 64 by providing a notch 72 in one face thereof deep enough to receive the tongue 68 and covered by a strip 74 of metal rigidly attached at its ends to the crossbar 64 on opposite sides of the notch 72.

So as to permit collapsing the easel to the smallest possible space, a notch 76 is provided in the

upper edge of the supporting arm 34 in that edge thereof which bears against the under surface of the shelf 20, this notch 76 being complementary to the cross sectional configuration of the crossbar 64 so that the crossbar can be slid longitudinally thereinto so as to assume a position underlying and extending longitudinally of the shelf 20. If desired, an additional bracket 78 may also be provided on the under surface of the shelf 20 in axial alignment with the notch 76 to aid in releasably retaining the crossbar 64 in position when the easel is collapsed.

A wedge 80 is slidably disposed under the upper U-shaped bracket 58 along with the slidable rod 56, the function of this wedge 80 being to releasably locate the slidable rod 56 in any selected position of vertical adjustment and thereby hold it at whatever extended position may be desired to support the map 66 in its optimum location.

When the easel is erected by having its legs 12, 14, and 16 separated to their most widely spread position, the shelf 20 will automatically be swung to its horizontal position so that a standard study case 82 of the type commonly employed by postal employees may be placed at the rear of the shelf 20, being tilted rearwardly toward the easel by reason of the longitudinal shelf rib 52. In such manner the forward position of the shelf is available for holding cards or other articles which can then be sorted into pigeonholes 72 of the case while checking locations or other data on the map 66 suspended above.

Accordingly, it will be seen that I have provided a highly useful and efficient and collapsible combination map-supporting and case-holding easel which has special utility for sorting letters, cards, and the like, but which may be used for a great variety of other purposes as well.

While I have shown and described in some detail a presently preferred embodiment of my easel assembly, it is to be understood that various modifications may be made in the construction and operation thereof within the scope of the subsequently claimed invention which is to be construed broadly and limited only by the prior art.

I claim:

1. A device of the character described comprising three legs pivotally joined together adjacent their upper ends, a transversely disposed shelf hingedly mounted on a pair of said legs so as to be swingable between a horizontally extending position and an upswung position wherein the upper face of said shelf abuts against said pair of legs, a link pivotally connecting said shelf and the third leg whereby said leg is extended rearwardly from its collapsed position in coplanar alignment with said pair of legs as said shelf is simultaneously swung down, and a T-shaped member having its center arm longitudinally slidable along one of said legs and its cross arm disposed adjacent the upper end thereof whereby a map may be suspended from the cross arm above the downswung shelf.

2. A device of the character described comprising three legs pivotally joined together adjacent their upper ends, a transversely disposed shelf hingedly mounted on a pair of said legs so as to be swingable between a horizontally extending position and an upswung position wherein the upper face of said shelf abuts against said pair of legs, and a link pivotally connecting said shelf and the third leg whereby said leg is extended rearwardly from its collapsed position in

coplanar alignment with said pair of legs as said shelf is simultaneously swung down.

3. A device of the character described comprising three legs pivotally joined together adjacent their upper ends, a transversely disposed shelf hingedly mounted on a pair of said legs so as to be swingable between a horizontally extending position and an upswung position wherein the upper face of said shelf abuts against said pair of legs, a link pivotally connecting said shelf and the third leg whereby said leg is extended rearwardly from its collapsed position in coplanar alignment with said pair of legs as said shelf is simultaneously swung down, a T-shaped member having its center arm longitudinally 15 slidable along one of said legs and its crossarm

disposed adjacent the upper end thereof whereby a map may be suspended from the crossarm above the downswung shelf, and means for removably mounting said crossarm upon the under surface of said shelf.
